UNITED STATES PATENT OFFICE.

JESSE R. HOWARD, OF BELOIT, WISCONSIN.

WINDOW SASH.

Application filed October 17, 1925. Serial No. 63,020.

To all whom it may concern:

Be it known that I, JESSE R. HOWARD, a citizen of the United States, and resident of Beloit, in the county of Rock and State of Wisconsin, have invented certain new and useful Improvements in Window Sashes; and I do hereby declare that the following is a full, clear, and exact description therof.

This invention relates to window sashes.

10 Objects of this invention are to provide a window sash which may be readily positioned within a window casing, and may be permanently secured therein in an air tight manner, and which is so constructed that it is provided with a stationary upper panel and a movable lower panel associated with a removably held screen whereby all of the advantages of the ordinary type of screened window are attained with, however, a relatively air tight construction when desired.

Further objects are to provide a window sash which may be easily positioned within a window casing, which has the appearance of the usual window, which is water proof, and which may be easily manipulated.

An embodiment of the invention is shown in the accompanying drawings, in which:

Figure 1 is a front view of the window sash.

30 Figure 2 is a vertical sectional view on the line 2—2 of Figure 1.

Figure 3 is a fragmentary enlarged sectional view on the line 3—3 of Figure 1.

Figure 4 is a sectional view also to an enlarged scale on the line 4—4 of Figure 2.

Referring to the drawings, it will be seen that the window sash is a unitary member and is provided with a rigid outer frame 1. Within this frame, a plurality of glass panels 2 are permanently positioned and are carried at their lower ends by means of a transverse member 3, as most clearly shown in Figure 2. The main portion 1 of the sash is provided with a groove 4 across its lower portion within which the bottom edge of the movable glass panel 5 is adapted to seat. This glass panel is guided by means of a finishing strip or flange member 6, as shown in Figures 2, 3, and 4. Preferably, the movable panel is provided with metallic binding strips for its edges, as indicated at 7 in Figures 2 and 3. These strips extend completely around the edges of the glass panel. The upper strip is provided with an inwardly directed lip or flange 8 which contacts with the portion 9 of the transverse

member 3 when the movable panel is closed. The side strips 7 are provided with manipulating handles 10. The lowermost of the strips 7 is provided with a downwardly slanting lip or flange 11 which contacts with the portion 12 of the window sash to prevent the entrance of rain.

A removable screen frame 13 is provided and is preferably equipped with an upwardly extending tongue 14 on its upper side cooperating with a corresponding groove formed in the transverse strip 3. This window sash fits snugly into the main body portion, and is provided with a beveled lower face, as indicated at 15, cooperating with a corresponding face in the main portion of the unitary member. This frame carries a screen 16 and is locked in place not only by the interlocking connection with the member 3 but also by means of a pair of flush bolts 17. Thus the screen frame is readily removable when desired.

It has been found that the slidable lower panel is sufficient to meet all requirements and preferably this panel is adapted to occupy any one of a plurality of positions without the use of balancing weights. This result is readily accomplished by providing a plurality of indentations 18 in the side strips 7 which bind the glass panel, as indicated in Figures 1 and 3. A pair of spring pressed plunger members, as indicated at 19, in Figure 3, are carried by the main body portion 1 and are adapted to snap into any one of the apertures 18 to thus yieldingly hold the panel in its adjusted position.

It is to be understood that the screen frame 13 may be removed and replaced by a storm sash in the winter time, if desired.

It will be seen that a very simple window sash has been provided which has the advantage of being a unitary structure and adapted to be bodily positioned within a window casing. Obviously, this unitary member may be secured in an air tight manner within the window casing and entrance of cold air wholly prevented.

Further, it will be seen that the device is provided with a slidable lower panel which may be readily manipulated and which does not require the use of counter-balancing weights.

Further, it has been found that the window answers all of the requirements of the

usual window and is very much cheaper in construction and more serviceable in operation.

Although the invention has been described in considerable detail, it is to be understood that the invention may be variously embodied and is, therefore, to be limited only as claimed.

I claim:

- 10 1. A window sash comprising a unitary member adapted to be set in the window casing and having a stationary upper panel, a slideable lower panel, said panels having glass panes, and a screen detachably secured outside of said lower panel, said screen and upper panel having interengaging fastening means.
- 15 2. A window sash comprising a unitary member having an upper stationary panel, a lower slideably mounted panel, said upper and lower panels having glass panes therein, a screen frame mounted outside of said lower panel and interlocked with the lower

end of said upper panel, a screen carried by said frame, and additional means for locking said screen frame in place.

3. A window sash comprising a unitary member having an outer frame, a permanently positioned panel in the upper portion of such frame, a slideably mounted lower panel carried by said frame, said panels having glass panes therein, a screen frame removably held outside of said movable panel, said lower movable panel having metal bindings around the edges of the glass pane therein, and said bindings having apertures formed in their outer sides, and a spring pressed plunger adapted to yieldingly snap to said apertures to temporarily hold said movable panel in any one of a plurality of adjusted positions.

In testimony that I claim the foregoing I have hereunto set my hand at Milwaukee, in the county of Milwaukee and State of Wisconsin.

JESSE R. HOWARD.
